(57) **CLAIM**

The ornamental design for refrigerant or cooling agent compressors, as shown.

DESCRIPTION

FIG. 1 is a front view of refrigerant or cooling agent compressors;

FIG. 2 is a rear view thereof;

FIG. 3 is a top view thereof;

FIG. 4 is a bottom view thereof;

FIG. 5 is a right-side view thereof;

FIG. 6 is a left-side view thereof; and,

FIG. 7 is a perspective view thereof.
